PNEUMATIC TUBE TERMINAL

Chester S. Jennings, Syracuse, N. Y., assignor to
 The Lamson Company, Syracuse, N. Y., a Corporation of Massachusetts

Application February 15, 1930. Serial No. 428,700

6 Claims. (Cl. 243—23)

This invention relates to pneumatic despatch systems and more particularly to an improved delivery terminal having novel air by-pass means adapted to permit adjustment of the carrier 5 cushioning effect to meet the requirements of any given conditions.

In the construction of delivery terminals it is customary to by-pass the air around the delivery end of the tube, and to connect the by-pass at 10 such a distance from the tube end as to form an air pocket of sufficient length to provide a cushioning effect for the arriving carrier. As the cushioning effect due to a given length of air pocket varies in accordance with several factors, 15 for example the length of the line, and as it is very desirable to bring about a positive discharge and at the same time one which is not too violent or noisy, it has heretofore been necessary to design the by-pass with reference to the lay-out of 20 each individual line. This consumes time and labor, both in determining the precise point at which the by-pass tube is to be connected and in the actual work of constructing and installing the parts to meet these requirements.

25 The present invention avoids the difficulty just noted since it provides means for adjusting the cushioning effect without requiring change in the actual length of the air pocket, so that a standard combination may be used in all ordinary 30 constructions. The invention is here shown as embodied in apparatus which is simple and efficient, and yet rugged and compact, and which at the same time is readily capable of embodiment in existing systems.

35 In the drawings:

Fig. 1 is a diagrammatic elevation of a pneumatic tube system comprising two stations connected by transmission tubes provided with appropriate terminals;

40 Fig. 2 is a side elevation, to larger scale, of a delivery terminal and a by-pass connection comprised in the system illustrated in Fig. 1;

Fig. 3 is a front elevation of the delivery terminal shown in Fig. 2;

45 Fig. 4 is a section to much larger scale, taken substantially along the line 4—4 of Fig. 5;

Fig. 5 is a section, to larger scale, taken substantially along the line 5—5 of Fig. 2;

50 Fig. 6 is a plan view of an adjusting quadrant; and

Fig. 7 is an edge view of the quadrant shown in Fig. 6.

The system illustrated in Fig. 1 comprises 55 transmission tubes 10 and 11 having despatch terminals 12 and 13 and delivery terminals 14

and 16, respectively. As herein illustrated, the improved by-pass means is shown as applied to the terminal 14 only, but it is to be understood that an equivalent arrangement may be used at the terminal 16 or at any terminal of generally 60 similar type. As shown in Figs. 1 and 2, the tube 11 communicates with the pump 18 (or other evacuating agency) by means of a by-pass pipe 17 connected to a hollow casting 21 which fits about the tube 11 at a point substantially removed from the extreme end of the tube. Within the casting the wall of the tube is provided with ports 22 through which air flows into the by-pass tube 17. The point of connection of the tube 17 and the location of the ports 22 in the 70 transmission tube 11 is selected to provide the maximum requisite cushioning effect for any installation, but in accordance with the present invention, means are provided for varying the cushioning effect in accordance with factors determined by each individual installation. To this end, in accordance with the present invention, a valve housing H is arranged at a point adjacent to the extreme end E of the delivery 75 terminal, such housing preferably comprising a sleeve-like casting 23 (Figs. 4 and 5) having oppositely directed sockets 24 and 26 respectively which receive the adjacent ends of tube sections constituting the by-pass tube 17. This casting also has a lateral boss 27 providing a socket 85 which receives a short tube 28 whose other end is received in a socket in a boss 27a projecting from a sleeve comprising parts 31 and 32 which are clamped around the tube 11. For clamping these parts together they may conveniently 90 be provided with projecting lugs 33 and 34 adapted to receive connecting bolts 36. Ports 29 in the side wall of tube 11 provide communication with the tube 28. The sleeve member 31 preferably has a channel for the reception of a gasket 37 engaging the outer wall of the transmission tube to assure a fluid-tight connection around the ports 29.

A wind-gate 38 is affixed, by means of screws 39, to a shaft 41 turning in journals in exterior 100 bosses 42 on the body of the casting 23. One end of this shaft is threaded to receive a nut 43 which holds a spring washer 44 against the adjacent boss 42. The other end of the shaft 41 extends outwardly beyond the other boss 42 and is connected to an adjusting quadrant 46 by means of a pin 47. As will be apparent from Figs. 6 and 7, the quadrant 46 has a boss 48 having a bore which receives the end of the shaft 41. The quadrant also has an arcuate slot 49 receiving the shank 105 110

of a set screw 51 (Fig. 5) engaging a threaded hole in a boss 52 on the body of the casting 23. The head of the set screw 51 is adapted to engage the quadrant to hold the latter in adjusted position when the set screw is tightened. This quadrant is provided with an operating handle 53.

Another wind-gate 54, which is similar in general to the wind-gate 38, is mounted on a shaft 56 journaled in exterior bosses 57 and 58 respectively of the casting 23. One end of the shaft is threaded to receive a nut 59 which holds a spring washer 61 against the adjacent boss 58. The other end of the shaft is received in and pinned to the boss 48^a of a quadrant 46^a by a pin 47^a. This quadrant 46^a which includes a handle 53^a may be identical with the quadrant 46 which cooperates with the wind-gate 38, and is held in adjusted position by adjustment of a set screw 51^a operating in a slot 49^a (Fig. 4) in the quadrant.

The wind-gate 38 is arranged to control the flow through the connection casing 24 and thus through the by-pass tube 17, while the wind-gate 54 is arranged to control the flow through the lateral tube 28. Preferably these wind-gates and the quadrants cooperating therewith are so arranged that the gate 38 may move from a substantially vertical or fully open position, as shown in Fig. 4, to a diagonal or partially open position; while the wind-gate 54 may move from a substantially vertical or closed position to a diagonal or partially open position.

In the operation of a system equipped with this improved valve mechanism, the gates 38 and 54 may both be left in a substantially vertical position, as shown in Fig. 4, to ascertain the behavior of the system; and if it is found that the proper cushioning effect is not obtained, this condition may be remedied by adjusting the positions of the respective gates 38 and 54. It will be seen that the gate 38 is adapted to restrict the flow through the by-pass tube and that this results in restricting the flow through the ports 22, while the gate 54 is adapted either to cut off entirely the flow through the lateral tube 28 and the ports 29 or to afford communication between the transmission tube and the by-pass tube through these ports. By adjusting the position of either of the quadrants 46 or of both of these quadrants, the desired cushioning effect may readily be obtained.

I claim:

1. In a transmission system, the combination of a transmission tube, a by-pass tube comprising aligned tube sections, valve mechanism comprising a body member adapted to receive the adjacent ends of the by-pass sections, a lateral connection between the body member and the transmission tube, a valve disposed in the body member and operable for cutting off the flow through the lateral connection, and means disposed in the body member for restricting the flow from the by-pass tube to the body member.

2. In a transmission system, the combination of a transmission tube, a by-pass tube comprising a pair of tube sections, valve mechanism comprising a housing having means for receiving the juxtaposed ends of the by-pass sections, a lateral connection between the housing and the trans-

mission tube, a wind-gate pivotally mounted in the housing and disposed for controlling the flow through the lateral connection, another wind-gate pivotally mounted in the housing and disposed for controlling the flow through the by-pass tube, and operating means for the wind-gates, the operating means being disposed on the exterior of the housing.

3. In a transmission system, the combination of a transmission tube, a by-pass tube comprising a pair of tube sections, valve mechanism comprising a housing having means for receiving the juxtaposed ends of the by-pass sections, a lateral connection between the housing and the transmission tube, a wind-gate for controlling the flow through the lateral connection, and another wind-gate for controlling the flow through the by-pass tube, an operating shaft for each wind-gate, the housing having journal openings in which the operating shafts are mounted for rotary movement, one end of each operating shaft extending through the housing, a quadrant affixed to said one end of each operating shaft, each quadrant having an operating slot, and a set screw disposed in each operating slot and affixed to the housing for holding the quadrant in adjusted position.

4. A valve housing having approximately oppositely disposed connections adapted to receive the ends of tubes and a lateral connection disposed between the first-mentioned connections, a wind-gate pivotally mounted in the housing for controlling the flow through one of the first-mentioned connections, means for limiting pivotal movement of the wind-gate from a fully open to a partially open position, and means for controlling the flow through the lateral connection.

5. A valve housing having approximately oppositely disposed connections adapted to receive the ends of tubes and a lateral connection disposed between the first-mentioned connections, a wind-gate pivotally mounted in the housing for controlling the flow through one of the first-mentioned connections, means for limiting pivotal movement of the wind-gate from a fully open to a partially open position, and means for controlling the flow through the lateral connection, another wind-gate pivotally mounted in the housing for controlling the flow through the lateral connection, and means for limiting pivotal movement of said other wind-gate from a substantially closed position to a partially open position.

6. In a transmission system a carrier transmission tube having a single valve delivery terminal and through which carriers pass freely, a by-pass tube including a housing and a tube section leading from said housing and connected at the other end to said transmission tube, a duct leading from the transmission tube to the housing, means for setting up a flow of air from the transmission tube into the housing through the by-pass tube section and the duct, and valves in said housing for independently controlling the flow of air through the tube section and the duct.

CHESTER S. JENNINGS.
